UNITED STATES PATENT OFFICE

2,145,809

ELEVATOR SYSTEM

Robert B. Taylor, Schenectady, N. Y., assignor to
General Electric Company, a corporation of
New York

Application June 12, 1937, Serial No. 147,949

13 Claims. (CL. 187—29)

My invention relates to elevator systems, more particularly to electric systems of control for elevators and has for its object selective automatic control means for decelerating and levelling the elevator for low speed and high speed runs.

In carrying out my invention I utilize vacuum tube control means such as disclosed in my U. S. Patent 1,910,190, dated May 23, 1933, and U. S. patent to John Eaton 1,910,204 of the same date.

10 In the operation of high-speed elevators it is desirable in making a stop from high speed to begin the deceleration of the elevator some distance, perhaps one floor or more, ahead of the floor at which the stop is to be made. For short 15 one floor runs, however, the elevator obviously does not have time to accelerate to full speed and therefore the deceleration for the one floor run for the most efficient operation should not begin until the elevator is fairly close to the floor.

20 In accordance with my invention I provide a special one floor run or low speed decelerating means with time control means for causing this decelerating means to take control for one floor runs.

25 For a more complete understanding of my invention reference should be had to the accompanying drawings, Fig. 1 of which is a diagrammatic representation of a system of elevator control embodying my invention, while Figs. 2 and 3 are diagrammatic views showing the control devices on the elevator and in the hatchway.

30 Referring to the drawings, in the specific embodiment of my invention shown, the elevator car 10 is raised and lowered by a main driving motor 11 which is connected in a Ward Leonard system with a generator 12 driven at a substantially constant speed by means of a suitable driving motor (not shown). The motor and generator are connected together in a permanent electrical circuit which includes a series winding 13 for the generator and also a commutating winding 14 for the generator. The motor 11 is controlled by controlling the direction and degree of energization of a separately excited field winding 15 for the generator 12 which field is connected to the direct current supply mains 16 and 17 for the desired direction of its excitation by means of reversing switches 18 and 19 operated respectively by the coils 20 and 21. The degree of excitation or strength of the motor field is controlled by suitably connecting resistances 22, 23, 24 and 25 in circuit with the field winding.

35 The control of the elevator is centered around the manipulation of the resistances 22 to 25 inclusive in the circuit of the shunt field winding

15. During the starting and acceleration of the motor 11, the field resistances are controlled by means of a suitable two-way car switch or controller 26 provided with a handle 27 which is thrown to the left, as seen in the drawings, for 5 operation of the elevator in a downward direction and to the right for the upward direction.

During deceleration, however, the resistances 22 to 25 inclusive are controlled automatically in response to the position of the car in the 10 hatchway, i. e., with respect to the floor to which the stop is to be made, so as to decelerate automatically the elevator at a uniform speed and at the maximum permissible rate without discomfort to the passengers. This position responsive 15 deceleration control mechanism embodies electron discharge control devices of the type disclosed in the above mentioned patents and therefore the devices themselves will be described but briefly herein.

20 Each device comprises an electric discharge device 28 of the three element type which is provided with a pair of coils 29 and 30 in its output and input circuits respectively. These coils are mounted so as to be in mutual inductive relation with each other, although spaced apart somewhat, and thereby maintain the discharge devices normally in an oscillating condition. Under this oscillating condition a suitable relay 25 in the output circuit of the discharge device is in effect deenergized, the radio frequency oscillating current being bypassed through a condenser 31 and the direct current in the output circuit at that time being very low in value as compared with the current required to operate the relay.

30 Seven of these deceleration control devices 32 to 38 inclusive are shown. The devices are mounted on the elevator in suitable positions such that as the elevator moves in the hatchway control vanes made of a suitable electrically conducting material, such as iron or copper, mounted in the hatchway adjacent each floor pass between the two coils 29 and 30 of each device and temporarily interrupt the inductive interlinkage between the coils whereby the relay for the discharge device is operated to control the elevator.

35 In Figs. 2 and 3 the arrangement of the control devices with respect to the vanes is shown for a typical installation with the elevator levelled at a floor. A levelling vane 39 is midway between the devices 36 and 38, the ends of 40 the vane not being between the coils of each device sufficiently to interrupt their oscillatory condition. A shorter vane 40 lies between the coils of the device 37 thus interrupting their os 45

50

55

cillatory condition. The upward one floor run control device 32 cooperates with the vane 41 while the downward one floor run control device 33 cooperates with the vane 42. In a similar 5 manner, the upward high-speed control device 34 cooperates with the vane 43 and the downward high-speed control device 35 cooperates with the vane 44.

Assuming now that the elevator is to be started in a downward direction, the operation of the control mechanism for each point of the controller 26 will be described in detail for the acceleration. Thereafter the deceleration for high-speed runs and one floor runs and the 15 levelling at the floor will be described.

With the controller in the off position shown in the drawings and the supply mains 16 and 17 energized, the coil 46 is energized, whereby the switches 47 and 48 operated by it are respectively opened and closed. This circuit for the coil 46 leads from supply mains 17 through conductor 49, switch 50, conductor 51, the coil 46 and the conductor 52 to the supply main 16.

25   Controller in first position on point 53

This energizes the coil 54 the circuit for which is from the supply main 17 through conductor 49, the controller to point 53, conductor 55, coil 54 and conductor 52 to main 16. The coil 54 opens the switches 56 and 57, but no control function is performed at that time.

Controller in second position on point 58

35   In this position the coils 21 and 60 are energized in series with each other. This circuit may be traced from main 17 through conductor 49, the controller, conductor 61, interlock switch 62, coil 21, coil 60 and conductor 63 to main 16. The coil 21 closes the reversing switches 19 thus connecting the field winding 15 across the supply mains in series with the resistances 22 and 24 in parallel with each other. This circuit for the field winding 15 leads from main 17 through conductor 49, resistance 22, the upper switch of 40 reversing switch 19, the coil 15, the lower switch and conductor 63 to main 16. The circuit for the resistance 24 is from the main 17 through the switch 68, the conductor 69, the resistance 24 and conductor 70 to the junction with resistance 22. This energization of the field 15 produces a low voltage in the generator 12 and the elevator starts at low speed. The coil 60 has meanwhile closed the switch 50a which energizes the brake coil 70a to release the brake. The 45 brake coil circuit is from conductor 49 through coil 70a, switch 50a and conductor 63 to main 16.

Also, the coil 60 opens the switch 50 thereby deenergizing the coil 46 whereby the switch 47 closes and the switch 48 opens after a predetermined time interval determined by its timing device 48a. It might be noted briefly here that the switch 48 controls the one floor run devices 32 and 33. Its timing device 48a is set to allow the switch 48 to open in about 1½ seconds. Consequently, if the controller 26 is moved to the off position within that period, which would be the case for a one floor run, the one floor run devices take control, as will be described more in detail hereinafter.

At the same time the coil 21 opened its interlock switch 71 and closed its interlock switch 72 in the output circuit of the down one floor run device 33, the switch 73 in the output circuit of

the down high speed control device 35, and also the interlock switches 74, 75, 76 and 77.

Controller in third position on point 78

In this position the coil 79 is energized, its 5 circuit being from the conductor 49 through the controller conductor 80, coil 79 and conductor 81 to main 16. The coil 79 closes its switch 82 thus connecting the resistance 25 in parallel with the two resistances 22 and 24 whereby 10 greater field excitation is supplied to the generator and the speed of the elevator is increased.

Also, the coil 79 closes its switch 83 thus completing a holding circuit for the coil 21, this circuit leading from main 17 through conductor 15 84, switch 83, conductor 85, switch 76, conductor 86, switch 62, coil 21 and, as before, through coil 60 and conductor 63 to main 16.

Likewise, coil 79 closes its switch 87 for its own holding circuit, this circuit leading from 20 conductor 84 through switch 87, conductor 88, switch 89, conductor 90, switch 77, conductor 80, coil 79 and conductor 81 to main 16.

Controller in fourth position on point 91 25

This closes the circuit for the coil 92 leading from the controller through conductor 93, the coil 92 and conductor 52 to main 16. The coil 92 closes its switch 94 thus connecting the resistance 23 in parallel with the other three resistances 30 for higher elevator speed.

Also, the coil 92 closes its own interlock switch 95 whereby a holding circuit is established for coil 92 from main 17 through conductor 96, switch 97, switch 98, switch 85 and switch 75, 35 conductor 93, coil 92 and conductor 52 to main 16.

The coil 92 also closes an interlock switch 99 in a circuit for the coil 100 as well as a switch 101 in the output circuit with the high-speed 40 deceleration unit 35.

This circuit for the coil 100 is from main 17 through conductor 96, switches 97 and 98, switch 99, switch 74, conductor 102, coil 100, switch 104, switch 105 and conductor 106 to main 16. 45

The coil 100 is now energized provided the car speed is high enough to close the switch 105 whose coil 108 is connected across the armature of the generator 12 and therefore responsive to its voltage and hence speed of the elevator. The 50 purpose of the switch 105 is to prevent a too rapid acceleration of the car in the event that the controller is moved immediately to the last position in contact with 91.

Assuming that the switch 105 is closed, the 55 coil 100 is energized and closes its switch 109 thus connecting the supply main 17 through the conductor 110 directly to the conductor 70. This short circuits the resistances 22 to 25 and gives maximum field excitation and maximum speed. 60

Deceleration from full speed

The controller 26 is thrown to its central off position but the elevator continues at full speed until the high-speed down vane 44 for the next 65 floor is reached by the down high-speed deceleration device 35. Because of the fact that the switch 111 is open the one floor devices 32 and 33 are inactive, but the high-speed device 35, assuming downward movement, is rendered active 70 by reason of the closing of the switch 101.

Therefore, when the device 35 reaches the vane 44 (Fig. 3) its output circuit is energized sufficiently to cause the relay coil 112 to lift up its armature thereby opening the switch 97 in cir- 75

One floor runs

cuit with the coils 92 and 100. The deenergization of these coils opens the switches 94 and 109 whereby the three resistances 22, 24 and 25 are inserted in parallel with each other in the circuit of field winding 15. The elevator now decelerates by regenerative braking to a predetermined low speed such as 160 or 170 feet a minute.

The output circuit of the device 35 may be traced from main 17 through conductor 110, switch 57, conductor 114, switch 47, coil 112, switch 101, switch 73, conductor 115, through the pilotron tube 116 and thence through the filament heating conductor 117 to the main 16.

15 At the same time of course the deenergization of the coil 92 opens the switches 95, 99 and 101, the switch 101 deenergizing the coil 112. Also, the switch 118 closes as well as the switch 97.

In the next decelerating operation the levelling devices take control. The first downward device 38 engages the vane 39 when the elevator is about 24 inches from the floor whereby the coil 119 is energized and opens the switch 89, thereby deenergizing the coil 79 whose switch 82 opens to disconnect the resistance 25. This leaves the resistances 22 and 24 only in the field circuit whereby the speed is still further reduced.

Also, the deenergization of the coil 79 opens its switch 83, but this does not deenergize the contactor coil 21 because of the closing of a holding switch 120 by the coil 119. Thus the circuit for the coil 21 is from main 17 through the switch 120, conductor 121 to the conductor 86 and thence as before.

35 The tube control circuit for the relay coil 119 leads from main 17 through conductor 110, switch 57, conductor 114, switch 118, conductor 122, coil 119 to the plate of the tube 123 and through the tube to the filament heating circuit 117.

40 As the elevator continues downward at still further reduced speed, the deceleration unit 37 reaches the vane 40 (Fig. 3). This preferably will occur when the elevator is about eight inches from the floor. It energizes the coil 124 which opens the switch 68 to deenergize the resistance 22 thus leaving the single resistance 22 in the field circuit. As a result the elevator decelerates to a very low speed. The circuit of the coil 124 is the same as for the coil 119 up to the conductor 122 from which it leads through the coil 124 to the plate of the tube 125 through the tube to the conductor 117 and thence to the main 16.

45 The final control operation occurs when the device 38 leaves the vane 39 whereby the coil 119 is deenergized and its switch 120 opened whereby the coils 21 and 60 are deenergized. This opens the contactor 19 whereby the field 15 is deenergized and opens the switch 50a whereby the brake coil 10a is deenergized and the brake 50 applied to stop the elevator at the floor.

55 In the event that the elevator overruns the floor the upward levelling device 36 is activated whereby the coil 126 is energized and the switch 127 closed, whereby the coils 20 and 60 are energized to reverse the elevator with the resistance 24 in the field circuit. This circuit for the coils 20 and 60 leads from main 17 through the conductor 128, switch 127 to the conductor 128a, switch 71, and thence through the coils 20 and 60 to the conductor 63 and the main 16. When the elevator moves back at this very low speed sufficiently to deenergize the coil 126, the field 15 is deenergized and the brake again applied to 60 stop the elevator accurately at the floor.

5 The control circuits previously described are set up with the exception of the energization of the coil 100 which is not energized by reason of the fact that the switch 104 is open. In other words, the accelerating circuits are set up so that the car accelerates with all four resistances 22 to 25 inclusive in the field circuit in parallel with each other.

10 The coil 129 is at this time energized by reason of the fact that the coil 54 was deenergized and its switch 56 closed before the switch 48 had timed open. Thus when the switch 56 closed, a circuit was established for the coil 129 from main 17 through conductor 110, switch 56, conductor 130, switch 48, conductor 131, coil 129, conductor 132, switch 50a, now closed, and conductor 63 to the main 16. The coil 129 closes its switch 133 and thus establishes a holding circuit for the coil 129 from main 17 through conductor 110, switch 56, conductor 130, switch 133, conductor 131 to the coil 129 and thence as before to the main 16. 15 Therefore, when the switch 48 opens after its predetermined time interval the coil 129 is not deenergized.

20 At the same time, the coil 129 opens its interlock switch 104 and closes its interlock switch 111 in the output circuit of the one floor run deceleration devices.

25 When the device 38 reaches its vane 42 (Fig. 3) the coil 134 is energized which opens the switch 98 and thereby deenergizes the coil 92. This opens the switch 94 leaving the three resistances 22, 24 and 25 in the field circuit in parallel with each other. The elevator now decelerates and the deceleration is continued by the levelling devices in accordance with the preceding description in 30 connection with the high speed stop.

35 The circuit for the coil 134 is from the main 17 through conductor 116, switch 57, switch 111, coil 134, switch 72, conductor 134a, the tube 135 and conductor 117 to main 16.

Long one floor run

40 Provision is also made for runs for floors of greater height than the other floors. For such runs the car switch is centered at once after being moved to the full running position. When the high-speed device 35 reaches its vane, however, the car will not have had time to attain full speed and therefore should not be decelerated as fast as from full speed for efficient operation.

45 The car accelerates with the same control circuits as for a one floor run, but has time to accelerate to a higher speed although not the maximum speed. The coil 129 is now energized as previously described. When the high-speed device 35 reaches its vane the coil 112 is energized and closes its switch 136 whereby the coil 137 is energized and closes its switch 138 whereby a portion 139 of the resistance 23 is connected in parallel with the other three resistances this connection being through the conductor 140. The effect of this is to give increased generator field and delay the deceleration.

50 Also the coil 112 opens its switch 97 whereby coil 92 is deenergized and switch 101 opened to 55 deenergize coil 112. The switch 136 is therefore opened very quickly after its closing whereby the coil 137 is deenergized and switch 138 released. The switch 138 is a time operated switch and is set to open under the control of suitable timing 60

65 70 75

means 141 is a very short interval of time, perhaps $\frac{1}{4}$ second, after which the switch 138 opens. Normal low-speed deceleration is now continued by the levelling units.

5 In view of the fact that the operation of the elevator in the upward direction is the same as for the downward direction except for some duplicate control means, it is believed unnecessary to describe this operation in detail. It 10 should be noted, however, that the first point 142 in the upward direction controls the same circuit for the coil 54 as the first point in the downward direction. This is also true of the third and fourth points 143 and 144. The interlock switches 146 to 151 inclusive on the down contactor 18 select the proper down units 32 and 34.

While I have shown a particular embodiment of my invention, it will be understood, of course, that I do not wish to be limited thereto since many 20 modifications may be made, and I therefore contemplate by the appended claims to cover any such modifications as fall within the true spirit and scope of my invention.

What I claim as new and desire to secure by 25 Letters Patent of the United States is:

1. A control system for elevators and the like comprising electric driving means for the elevator, a controller for controlling said driving means to start and accelerate said elevator, a plurality of means for controlling said driving means to decelerate said elevator from respectively high and low speeds, said means being responsive to the position of the elevator and said high-speed means being effective at a greater distance from 30 the desired stop, and means responsive to movement of said controller for selectively rendering one of said decelerating means effective to decelerate said elevator.

2. A control system for elevators and the like comprising electric driving means for the elevator, a manually operated controller for controlling said driving means to start and accelerate said elevator, low-speed and high-speed decelerating means for controlling said driving means to decelerate said elevator, said decelerating means being responsive to the position of the elevator and said high-speed decelerating means operating when the elevator is a greater distance from the floor than said low-speed decelerating means, and time controlled mechanism responsive to movement of 45 said controller for rendering said low-speed decelerating means operative to decelerate said elevator from a low speed.

3. A control system for elevators and the like comprising electric driving means for the elevator, a manually operated controller for controlling said driving means to start and accelerate said elevator, low-speed and high-speed decelerating means for controlling said driving means to decelerate said elevator, said decelerating means being responsive to the position of the elevator and said high-speed decelerating means operating when the elevator is a greater distance from the floor than said low-speed decelerating means, and time controlled mechanism responsive to movement of 50 said controller for rendering said low-speed decelerating means operative and for disabling said high-speed decelerating means to decelerate said elevator from a low speed.

70 4. A control system for elevators and the like, comprising the combination with a hatchway and a car movable in said hatchway, electric driving means for said car, reversing switches for controlling said driving means for forward and re-

75 driving means for controlling the acceleration and deceleration of said driving means, electromagnetically operated control switches for controlling said resistances, a controller for controlling said reversing and control switches to start and accelerate said car, low-speed and high-speed control devices for said control switches mounted on said car, a pair of members mounted in said hatchway at different distances from the selected floor in position to come into cooperative relation respectively with said control devices and thereby operate said control switches to control the deceleration of the car, the member for said low-speed control device being nearer the floor, means normally disabling said low-speed control device and means controlled by said controller for rendering effective said low-speed control device.

5. A control system for elevators and the like, comprising the combination with a hatchway and a car movable in said hatchway, electric driving means for said car, reversing switches for controlling said driving means for forward and reverse operation, resistances in circuit with said driving means for controlling the acceleration and deceleration of said driving means, electromagnetically operated control switches for controlling said resistances, a controller for controlling said reversing and control switches to start and accelerate said car, low-speed and high-speed control devices for said control switches mounted on said car, a pair of members mounted in said hatchway at different distances from the selected floor in position to come into cooperative relation respectively with said control devices and thereby operate said control switches to control the deceleration of said car, the member for said low-speed control device being nearer the floor, means normally disabling said low-speed control device, and time controlled means responsive to movement of said controller to its off position 40 for rendering effective said low-speed control device.

6. A control system for elevators and the like, comprising the combination with a hatchway and a car movable in said hatchway, electric driving means for said car, reversing switches for controlling said driving means for forward and reverse operation, speed control means for controlling the acceleration and deceleration of said driving means, electromagnetically operated control switches for controlling speed control means, a manually operated controller for controlling said reversing and control switches to start and accelerate said car, low-speed and high-speed electron discharge devices having input and output circuits mounted on said car, a pair of devices mounted in said hatchway at different distances from the selected floor in position to come into cooperative relation respectively with said discharge devices and thereby control said output circuits, the device for said low-speed discharge device being nearer the floor, means included in said output circuits for operating said control switches to control said speed control means and thereby control the deceleration of said car, means normally disabling said low-speed discharge device, and time controlled means responsive to movement of said controller for rendering effective said low-speed discharge device.

7. A control system for elevators and the like, comprising the combination with a hatchway and a car movable in said hatchway, electric driving means for said car, reversing switches for controlling said driving means for forward and re-

verse operation, resistances in circuit with said driving means for controlling the acceleration and deceleration of said driving means, electromagnetically operated control switches for controlling said resistances, a manually operated controller for controlling said reversing and control switches to start and accelerate said car, low-speed and high-speed electron discharge devices having input and output circuits mounted on said car, a pair of metallic vanes mounted in said hatchway at different distances from the selected floor in position to come into cooperative relation respectively with said discharge devices upon movement of said car and thereby control said output circuits, the vane for said low-speed discharge device being nearer the floor, means included in said output circuits for operating said control switches to vary the amount of resistance in said circuit to control the deceleration of said car, means normally disabling said low-speed discharge device, and time controlled means responsive to movement of said controller to its off position for rendering effective said low-speed discharge device and for disabling said high-speed discharge device.

8. A control system for elevators and the like, comprising electric driving means for the elevator, a manually operated controller provided with a plurality of positions for controlling said driving means to start and accelerate said elevator, decelerating means for controlling said driving means to decelerate said elevator, said decelerating means being responsive to the position of the elevator, a normally open switch in a control circuit for said decelerating means, means operated by said controller when in one position for closing said switch, means actuated by movement of said controller to a second position for opening a second switch in said control circuit, means actuated by movement of said controller to a third position for releasing said first switch and for closing a third switch in said control circuit, time responsive means for delaying the opening of said first switch for a predetermined time interval, and means actuated by movement of said controller to a final position for holding said third switch closed when said controller is returned to said one position, whereby when said controller is returned to said one position before said first switch has opened, said second switch closes to energize said decelerating means for deceleration of said elevator from a low running speed.

9. A control system for elevators and the like, comprising electric driving means for the elevator, a manually operated controller provided with a plurality of positions for controlling said driving means to start and accelerate said elevator, decelerating means for controlling said driving means to decelerate said elevator, said decelerating means being responsive to the position of the elevator, a normally open switch in a control circuit for said decelerating means, means operated by said controller when in one position for closing said switch, means actuated by movement of said controller to a second position for opening a second switch in said control circuit, means actuated by movement of said controller to a third position for releasing said first switch and for closing a third switch in said control circuit, time responsive means for delaying the opening of said first switch for a predetermined time interval, means actuated by movement of said controller to a final position for holding said third switch closed when said con-

troller is returned to said one position, whereby when said controller is returned to said one position, before said first switch has opened, said second switch closes to energize said decelerating means for deceleration of said elevator from a low running speed, and decelerating and leveling control means for said driving means responsive to the position of the elevator for decelerating and levelling the elevator and for thereafter opening said third switch.

10. A control system for elevators and the like, comprising electric driving means for the elevator, a manually operated controller provided with a plurality of positions for controlling said driving means to start and accelerate said elevator, decelerating means for controlling said driving means to decelerate said elevator, said decelerating means being responsive to the position of the elevator, an electromagnetically operated switch in a control circuit for said decelerating means energized to closed position when said controller is in one position, means operated by movement of said controller to another position for opening a second switch in said control circuit, means operated by movement of said controller to a third position for deenergizing said first switch and for closing a third switch in said control circuit, time responsive means for delaying the opening of said first switch, and means operated by movement of said controller to a final position for establishing a circuit to maintain said third switch closed when said controller is returned to said one position, whereby when said controller is returned to said one position before said first switch has opened, said second switch closes to energize said decelerating means for deceleration of said elevator from a low running speed.

11. A control system for elevators and the like, comprising electric driving means for the elevator, a manually operated controller provided with a plurality of positions for controlling said driving means to start and accelerate said elevator, decelerating means for controlling said driving means to decelerate said elevator, said decelerating means being responsive to the position of the elevator, a first normally closed switch for closing a circuit when the controller is in its off position, to close a second switch in a control circuit for said decelerating means, means operated by movement of said controller to a first position for opening a third switch in said control circuit, means operated by movement of said controller to a second position for opening said first switch to deenergize said second switch and for closing a fourth switch in said control circuit, time responsive means for delaying the opening of said second switch, and means operated by movement of said controller to a final position for establishing a holding circuit to maintain said first and fourth switches respectively open and closed when said controller is returned to its off position, whereby when said controller is returned to its off position before said second switch has opened, said third switch closes to energize said low-speed decelerating means for deceleration of said elevator from a low running speed.

12. A control system for elevators and the like, comprising electric driving means for the elevator, a manually operated controller provided with a plurality of positions for controlling said driving means to start and accelerate said elevator, low-speed and high-speed decelerating means for controlling said driving means to decelerate said

elevator, said decelerating means being responsive to the position of the elevator and said high-speed decelerating means operating when the car is a greater distance from the floor than said low-speed decelerating means, a first normally closed switch for closing a circuit when the controller is in its off position to close a second switch in a control circuit for said low-speed decelerating means, means operated by movement of said controller to a first position for opening a third switch in said control circuit, means operated by movement of said controller to a second position for opening said first switch to deenergize said second switch and for closing a fourth switch in said control circuit, time responsive means for delaying the opening of said second switch, and means operated by movement of said controller to a final position for establishing a holding circuit to maintain said first and fourth switches respectively open and closed when said controller is returned to its off position, whereby when said controller is returned to its off position before said second switch has opened, said third switch closes to energize said low-speed decelerating means for deceleration of said elevator from a low running speed.

13. A control system for elevators and the like, comprising electric driving means for the elevator, a manually operated controller provided with a plurality of positions for controlling said driving means to start and accelerate said elevator, low-speed and high-speed decelerating means for controlling said driving means to decelerate said elevator, said decelerating means

being responsive to the position of the elevator and said high-speed decelerating means operating when the car is a greater distance from the floor than said low-speed decelerating means, a first normally closed switch for closing a circuit when the controller is in its off position to open a second switch to deenergize said high-speed decelerating means and to close a third switch in a control circuit for said low-speed decelerating means, means operated by movement of said controller to a first position for opening a fourth switch in said control circuit, means operated by movement of said controller to a second position for opening said first switch to deenergize said second and third switches and for closing a fifth switch in said control circuit, time responsive means for delaying the opening of said second and third switches, means operated by movement of said controller to a final position for establishing a holding circuit to maintain said first and fifth switches respectively open and closed when said controller is returned to its off position whereby when said controller is returned to its off position before said second and third switches have closed and opened, said fourth switch closes to energize said low-speed decelerating means for deceleration of said elevator from a low running speed, and time controlled means operated by said high-speed decelerating means after energization of said low-speed decelerating means for decreasing temporarily the rate of deceleration of said elevator.

ROBERT B. TAYLOR.
